A CORPORATION OF MASSACHUSETTS.

IMPACT TOOL.

1,427,556.

Specification of Letters Patent. Patented Aug. 29, 1922.

Application filed March 24, 1921. Serial No. 455,025.

To all whom it may concern:

Be it known that we, WILLIAM H. SHORTELL and FRANK L. SUTLIFFE, citizens of the United States, residing at West Haven, in 5 the county of New Haven and State of Connecticut, have invented new and useful Improvements in Impact Tools, of which the following is a specification.

This invention relates to an impact tool 10 such as a nail-set, which includes an elongated body formed at one end to engage a nail head, or otherwise formed according to the function of the tool, and provided at its opposite end with a flat-sided enlargement 15 adapted to sustain the blows of a hammer, and to prevent the tool from rolling when laid on a flat surface, the tool being composed essentially of two members, one of which is substantially cylindrical and forms 20 the body, while the other is externally polygonal and forms the enlargement.

The object of the invention is to provide an impact tool the members of which are adapted to be engaged with each other first 25 by friction, caused by the engagement of straight knurled teeth on the body with the wall of a socket in the enlargement, and then positively by the radial outward displacement of portions of said teeth.

30 The invention is embodied in the improvements hereinafter described and claimed.

Of the accompanying drawings forming a part of this specification,—

Figure 1 is a side view of a nail-set embodying the invention.

Figure 2 is a side elevation of the body member alone.

Figure 3 is an enlarged section on line 3—3 of Figure 1.

40 Figure 4 is a section on line 4—4 of Figure 3.

Figures 5, 6 and 7 represent a modification, Figure 5 being a side view of a portion of the body member, Figure 6 a sectional view of the enlargement-forming member or cap, and Figure 7 is a sectional view showing the body member and cap positively interlocked.

The same reference characters indicate the 50 same parts in all of the figures.

We will first describe the preferred construction shown by Figures 1, 2, 3, and 4. The body member 12 is of substantially cylindrical form, its axis being elongated.

One portion of the said member is tapered 55 and cupped at 13 to engage a nail head. A zone of the body member at the opposite end portion is preferably knurled to provide straight longitudinal teeth 15, parallel with the longitudinal axis of the body member and adapted to indent the wall of a socket 17 in a cap member 16 forming the 60 enlargement of the tool. Another zone of the body member may be provided with diamond knurling 19, to afford a suitable 65 gripping surface.

The cap member 16 has a head 20 closing one end of the socket 17, and said socket is formed to have a close driving fit on the 70 knurled teeth 15, so that when the cap member is forced onto the body member, a firm frictional engagement is set up between the members, the teeth 15 slightly indenting the wall of the socket.

The cap member is provided with means 75 whereby hammer blows sustained by the head 20, are caused to spread the end face of the body member within the cap, and thus displace portions of the teeth 15 radially outward into positive interlocking engagement with the cap member, said means being embodied in a hardened steel ball 22, interposed between said end face and the head 20. To facilitate the spreading of the end face, we provide it with a recess 23, receiving a portion of the ball.

It will now be seen that when the cap member has been frictionally engaged with the body member, the subsequent use of the tool involves a positive and constantly maintained 90 interengagement between said members.

In the modification shown by Figures 5, 6, and 7, the body member has a reduced zone provided with a straight knurling.

We find that by knurling a cylindrical 95 end portion of the body member, we are enabled to secure a close frictional fit between the wall of the socket 17 and the portion of the body member inserted therein, without the expense which would be involved 100 by the operation of making the diameters of the socket and of the inserted portion of the body member such that they will exactly fit each other, no teeth being employed. Moreover, the radially expanded portions 105 of the knurled teeth engage the socket wall more effectively than would a radially expanded smooth surface.

In both of the embodiments of the invention illustrated it will be seen that the cap and body of the tool will be initially engaged by friction, so that they are not liable to be disengaged while being handled in stock, prior to actual use, and when used the two parts will be positively interlocked so that relative longitudinal movement between them is absolutely prevented.

10 By making the implement in two parts, the body being of cylindrical form throughout its length and the polygonal shaped cap being formed separately the manufacture thereof is expedited and after the completed 15 tool has been used the cap which prevents rotation of the tool is as positively interlocked with the body as if it were integral therewith.

It is obvious that the improvement hereinafter claimed may be embodied in various 20 impact tools, such as a drive punch, a pin punch, a center punch, and a prick punch, and adapted to be operated by blows of a hammer, the tool in each case having an acting 25 end shaped in accordance with the function of the tool, the acting end in the example here shown being cupped to engage a nail head.

We claim:

30 1. An impact tool comprising an elongated body member having an acting end and a cylindrical portion at its opposite end

knurled to form straight longitudinal teeth parallel with the axis of the body member, 35 the end face of the knurled portion being provided with a recess, a cap member having a solid end forming a head and a socket which is open at one end of the cap member and closed at the opposite end by said head, 40 the socket wall being formed to bear upon and be indented by the teeth of the knurled portion, and a hardened ball interposed between said recess and the head of the cap member and operable by force exerted on 45 said head to spread the inner end of the knurled portion and displace portions of the teeth thereof radially outward into positive interlocking engagement with the cap member. 50

2. An impact tool comprising an elongated body member having an acting end and a cylindrical portion at its opposite end, and a cap member initially formed, separate from the body having a solid end forming a head and a socket which receives the cylindrical end of the body, the cap and body being positively interlocked and prevented from having relative longitudinal movement by radially deflected portions of the engaging surfaces of said parts. 55

In testimony whereof we have affixed our signatures.

WILLIAM H. SHORTELL.
FRANK L. SUTLiffe.
